MILKING MACHINE COLLECTOR VESSEL OR THE LIKE

Lawrence Bouma, 12375 S. Euclid Ave., Ontario, Calif.

Filed Mar. 20, 1961, Ser. No. 64,377

Term of patent 14 years

(Cl. D23—1)

FIG. 1 is a side elevational view of a milking machine collector vessel or the like showing my new design;

FIG. 2 is a top plan view thereof;

FIG. 3 is a rear elevational view thereof;

FIG. 4 is a front elevational view thereof; and

FIG. 5 is a bottom view thereof.

The undisclosed side of the vessel is substantially the same in appearance as the side shown.

I claim:

The ornamental design for a milking machine collector vessel or the like, substantially as shown and described.
